PAPER CLIP

George B. Tremmel, Washington, D. C., assignor
of fifty per cent to Harold B. Alderson, Wash-
ington, D. C.

Application July 21, 1939, Serial No. 285,798

3 Claims. (Cl. 40—23)

This invention relates to a paper clip and more particularly to a type thereof which is adapted to be used as an advertising medium or a means of identification.

5 An object of the invention is to arrange a sheet of material of any character with a convoluted wire clip so that a plurality of papers may be removably secured together; the sheet of material having a legend or identification 10 means carried thereby.

A further object of the invention is to provide a paper clip having a sheet of material associated therewith in such a manner that the assembled structure may be continually used without injuring 15 the assembly as a unit.

An additional object of the invention is to provide a portion of the sheet of material so that it will be reinforced against longitudinal stresses transmitted thereto during service.

20 The above and numerous other objects will become apparent from the succeeding description considered together with the accompanying drawing which illustrates an exemplification of the present invention and wherein:

25 Figure 1 shows a front elevational view of a convoluted wire member or clip.

Figure 2 shows an elevational view of a sheet of material removed from an assembled unit.

Figure 3 shows the relation between the member of Figure 1 and the sheet of material of Figure 2 before they are secured together.

Figure 4 shows an assembled clip or member embodying a form of the present invention.

Figure 5 is an enlarged horizontal sectional view taken along the lines 5—5 of Figure 4, looking in the direction of the arrows.

Figure 6 is an enlarged vertical sectional view taken along the lines 6—6 of Figure 4, looking in the direction of the arrows.

40 Referring now in detail to the drawing, wherein like reference characters designate like parts, the numeral 1 indicates generally a conventional form of paper clip employed to be interlocked with the marginal edges of two or a plurality of 45 sections of paper for maintaining them in assembled relation. It will, of course, be clearly understood that the disclosed clip 1 is merely illustrative of the type which may be employed and is not intended as a limitation of the present invention.

50 Numerous other types of clips may be employed with the same advantages enjoyed as by the use of the illustrated clip.

As is common with clips of the character under immediate consideration, the clip is formed of 55 wire and presents an inner convolution 2 and an

outer convolution 3, both of which are disposed in a common plane and may be moved transversely or away from one another to present an opening for the insertion of a single or a plurality of sections of paper therebetween. The outer convolution is, by reason of its extending around the inner convolution, of greater dimensions than the inner convolution, and for this reason its free extremity 4 is in spaced relation to a corresponding or free extremity 5 of the inner convolution. 10 The inner and outer convolutions are joined or integrally connected by a loop or arcuate portion 6 forming the extremity of the clip opposed from the convolution extremities 4 and 5.

A sheet of material, generally designated by 15 the numeral 7 and illustrated in Figure 2 as it appears before assembly with the clip, is elongated or rectangular in form and is of a width slightly greater than the over-all width of the clip outer convolution for the purpose to be hereinafter 20 explained. The sheet 7 may be of a transparent cellulose compound or, if desired, may be formed of a relatively thin durable paper, no particular character of material being at present preferred.

25 Consideration has been given to the serviceability of the assembled unit, and therefore the sheet has been shaped so that it may only overlie one side of the clip, leaving the other side thereof substantially free in order to eliminate a constant wear to which it may otherwise be subjected in service. It will, of course, be understood that if the sheet were to extend completely or substantially so about a convolution of the clip frictional forces would be created on a line contact between the enveloped convolution and the adjacent paper of the plurality thereof being secured together. These frictional forces would result in the severance of the sheet of material along the line contact referred to and the unserviceability of the assembled clip for the purpose for which it was designed and intended. Also, if the sheet of material were to envelop a portion of the outer convolution, the envelope could only extend to the proximity of the free extremity 5 of the inner convolution for, if it were extended further longitudinally of the clip so as to envelop the inner convolution, the assembly could not be used since the two convolutions could not be spread apart for the reception of a single or a plurality of sections of paper.

30 For the above-enumerated reasons, therefore, the sheet of material is made of a width so that, upon application thereof to a clip, it will extend across a single side of the outer convolution and the lateral free edges 8 of the sheet will only

extend about and be in intimate contact with a segment, preferably a quarter, of the wire, as most clearly illustrated in Figure 5 of the drawing. The segment of the sheet, which bears against the 5 portion of the wire forming the outer convolution, is secured thereto by means of a gum compound, which has been found to be desirable when the sheet is formed of a cellulose compound, or any preferred adhesive. Since the sheet is to carry 10 a legend, illustrative of which are the letters appearing thereon in Figure 2, it is desirable to obtain a relatively large area for the accommodation of the legend, and for the accomplishment of this purpose the sheet extends longitudinally 15 of the outer convolution for substantially the entire length thereof.

It has been found that unless the extremity of the sheet adjacent and to be secured to the acute extremity 4 of the outer convolution is particularly shaped it will not conform to the free extremity 4 and also that the sheet, in this intermediate area, will be creased or wrinkled to present not only an unsightly condition but also an undesirable one. To eliminate this creasing or 20 wrinkling of the sheet an extremity is, therefore, cut inwardly toward the center line thereof to present tapered or inclined edges 9 which, when the sheet is assembled with the clip, reference being had to Figures 3 and 4, extend across the extremity 4 to leave portions thereof disclosed. The inclined edges 9 of the sheet merge into substantially parallel edges 10 of the sheet which are spaced apart a distance less than that between the lateral free edges 8 to thereby form a tongue, 25 35 extension or prong 11. The prong is wrapped around the free extremity of the outer convolution to present a reentrant member which is secured by any approved means, such as the previously mentioned adhesive, to the free extremity 40 of the outer convolution and the reverse side of the sheet. This prong construction and its association with the clip afford a means whereby the adhesive securing the side marginal edges of the sheet to the outer convolution is relieved of longitudinal stresses to which it might be subjected 45 during service of the clip. The prong extending to what may be termed the reverse side of the clip is not objectionable since, in actual service, it rarely happens that the free extremity of the 50 outer convolution comes into intimate contact with the papers to be attached or maintained in assembled relation, and hence it would not be subjected to frictional forces to which reference has been previously made.

55 It will, of course, be clearly understood that various changes and alterations may be made to the illustrated and described construction without departing from within the spirit and scope of the appended claims.

60 I claim:

1. In combination with a wire clip formed by

an inner and an outer convolution positioned in a common plane and having free extremities of the convolutions spaced from one another, a rectangular sheet of material adapted to carry a legend and being of a width slightly greater than the width of the outer convolution and of a length substantially equal to said outer convolution, the sheet having longitudinal edges thereof extending around and secured to only a quarter segment of the wire forming the outer convolution, and a 10 prong extending from one end of said sheet intermediate said longitudinal edges; said prong being adapted to be secured to said free extremity of said outer convolution and said sheet intermediate the planes of said longitudinal edges. 15

2. In combination with a wire clip formed by an inner and an outer convolution adapted to be separated for attachment to a marginal edge of a section of paper and having free extremities of the convolutions spaced from one another longitudinally of the clip, a sheet of material adapted to carry a legend and being of a width slightly greater than the width of said outer convolution and of a length substantially equal to said outer convolution, said sheet adjacent longitudinal edges thereof extending around and being secured to only a segment less than half the circumference of the wire forming said outer convolution, sloping edges on said sheet extending inwardly from said longitudinal edges and extending across the free extremity of said outer convolution, and substantially parallel edges of said sheet merging with said sloping edges defining a prong therebetween; said prong being bent around said outer convolution free extremity and secured to said 35 sheet.

3. In combination with a wire clip formed by an inner and an outer convolution adapted to be separated for attachment of the clip to a marginal edge of a section of paper and having free extremities of the convolutions spaced from one another longitudinally of the clip, a sheet of material adapted to carry a legend and having a width slightly greater than the width of said outer convolution and of a length substantially equal 40 to said outer convolution, said sheet extending across said outer convolution and having portions adjacent longitudinal edges thereof extending around and being secured to a segment of the wire less than half the circumference of the 45 wire forming said outer convolution, inclined edges extending inwardly of said sheet from said longitudinal edges, and substantially parallel edges of said sheet spaced apart a distance less than said longitudinal edges forming continuations of said inclined edges to define an extension therebetween; said prong being bent around said outer convolution free extremity and extending in a direction toward the free extremity of said inner convolution to be attached to said sheet. 55
